(57) **CLAIM**

The ornamental design for a toy gun target set, as shown and described.

DESCRIPTION

FIG. 1 is a perspective view of a toy gun target set showing my new design;

FIG. 2 is an exploded perspective view thereof;

FIG. 3 is a front view of FIG. 1;

FIG. 4 is a back view thereof;

FIG. 5 is a left side showing the target portion separately for ease of illustrations;

FIG. 6 is a right side view thereof;

FIG. 7 is a top plan view of FIG. 1;

FIG. 8 is a bottom plan view of FIG. 1; and,

FIG. 9 is an enlarged view of portion of FIG. 1.

The long-short dash lines in FIGS. 1 and 9 are used to illustrate bounds of the magnified portion of the toy gun target set that form no part of the claimed design, and the even dash-dash broken lines depict portions of the toy gun target set that form no part of the claimed design.
